UNITED STATES PATENT OFFICE.

FREDERICK W. WILLE, OF WEST OAKLAND, CALIFORNIA.

WINDOW-CLEANER.

SPECIFICATION forming part of Letters Patent No. 730,183, dated June 2, 1903.

Application filed June 20, 1901. Serial No. 65,383. (No model.)

To all whom it may concern:

Be it known that I, FREDERICK W. WILLE, a citizen of the United States, residing at West Oakland, in the county of Alameda and State of California, have invented certain new and useful Improvements in Window-Cleaners, of which the following is a specification.

My invention relates to improvements in window-cleaners, the object of my invention being to provide a device of this character which shall be cheap and simple in construction and convenient and effective in operation.

My invention therefore resides in the novel construction, combination, and arrangements of parts for the above ends, hereinafter fully specified, and particularly pointed out in the claims.

In the accompanying drawings, Figure 1 is a perspective view of my improved device with the brush inserted therein. Fig. 2 is a vertical section of the same, the brush being removed. Fig. 3 is a vertical section of the brush detached, and Fig. 4 is a plan view of the same.

Referring to the drawings, 1 represents the body of the window-cleaner, which is oblong in plan view and tapering or wedge shape in longitudinal section. From said body extends a curved handle 2, projecting outwardly and rearwardly, so that the hand of the operator shall be removed from the surface of the window sufficiently for convenient operation. An important feature of the improvement resides in the tapering form of the body 1, the effect of which is to throw the handle 2 to the rear when the rubbing-surface 3 of said body is in contact with the window. Said rubbing-surface 3 is provided by means of a sheet of rubber united at the upper end with a projecting piece of rubber 4, attached to the rear side 5 of the body, the two attached edges of the pieces 3 and 4 of rubber forming a lip 6, adapted to scrape closely the surface 45 of the window.

Upon the rear side 5 of the body is secured a sheet of galvanized iron or tin 7, said sheet being secured to said body at the sides, as shown at 8, and standing out a short distance 50 from the body in the middle, as shown at 9. A socket is thereby formed for the tongue 10 of a brush, said tongue being formed of two

sheets of galvanized iron or tin secured together and inclosing therebetween a thick piece of felt or other suitable material 11 to 55 form a brush. The lip of said holder which holds said brush extends out from the holder proper at an angle, so that when the edge of the brush is placed upon the window substantially at right angles thereto the main 60 body of the window-cleaner extends at such an angle as to permit sufficient pressure to be conveniently applied to the window.

Upon the back of the body 5 is secured a bearing 12 for a clamp member 13, said clamp 65 member comprising a piece of wire bent to form two eyes 14, pivoted on said bearing, and said wire extending rearwardly and downwardly on both sides of the handle and then in front of the handle and being bent at right 70 angles at this end to form a lip to rest against the lower edge of the hand. Said wire extends in the other direction from said pivot to the back of the body of the window-cleaner and is there extended outwardly or laterally 75 on each side to form a clamping-jaw 15, adapted to rest upon the back of the socket-plate for the brush-holder.

The operator in taking hold of the device by the handle will extend his fingers around 80 in front of the handle 16 of the clamp, so as to grasp the two together, thereby causing the clamp-jaw to press firmly down upon the back of the socket-piece and hold the brush in position. Moreover, when it is desired to 85 use a piece of chamois leather for cleaning the window this can be done by inserting the chamois between the clamping-jaw and the back of the socket-piece and extending said chamois in front of the surface of the rubber 90 3. A piece of dampened chamois may be first inserted and the window rubbed therewith, and then a clean dry cloth may be substituted therefor for polishing the window.

In using the device as a window-cleaner 95 the brush, which has been previously moistened, is first applied to the surface of the window to discharge water thereon, and then the device is turned in the hand, and the rubber is applied to the surface of the window to 100 spread the water over said surface and to clean the window by means thereof. When another part of the window has to be cleaned, the operation is repeated, moisture being ap-

plied by the brush and then friction being applied to the moistened surface by means of the rubber.

I claim—

- 5 1. As an article of manufacture, a window-cleaner comprising a body portion, a socket on the back of said body, a brush-holder having a stem in said socket, and a clamp member, pivoted on the rear side of said body and having a handle extending downward in front of the handle of the body, and a clamping-jaw extending upward from said pivot and adapted to rest upon the back of the socket, substantially as described.
- 10 15 2. A window-cleaner comprising a body portion having a flat side and a handle secured thereto, a sheet-metal plate secured at its

sides on said flat side, the central portion thereof being slightly elevated above said flat side to form a narrow socket, a brush-holder comprising two sheet-metal plates separated at their upper ends to receive a brush therebetween, and brought together at their lower ends, said lower ends being reduced in width to fit within said socket, and a brush clamped 25 between the separated upper ends of said plates, substantially as described.

In witness whereof I have hereunto set my hand in the presence of two subscribing witnesses.

F. W. WILLE.
